(57) **CLAIM**

The ornamental design for a magnetic disc storage, as shown and described.

DESCRIPTION

FIG. 1 is a front, plan and right side perspective view of a magnetic disc storage showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof;

FIG. 8 is a sectional view thereof taken in the direction of lines 8—8 in FIG. 2; and,

FIG. 9 is a sectional view thereof taken in the direction of lines 9—9 in FIG. 2.
